WATER SKIS

Cosimo V. Cravotta, Pittsburgh, Pa., assignor to Cravotta Brothers, Inc., East McKeesport, Pa., a corporation of Pennsylvania

Filed May 27, 1960, Ser. No. 32,374
1 Claim. (Cl. 9—310)

This invention relates to water skis, more especially water skis made at least in major part of wood. More particularly, my invention pertains to a water ski made up of a plurality of pieces for one or more reasons of economy, performance, convenience and strength. Further, this invention includes skis which are built up of wood pieces in whole or in part with, optionally, side wings and/or removable front and rear end pieces.

Water skis made in accordance with my invention provide marked advantage in one or more aspects of economy, performance, convenience and strength. For example, heretofore it has been considered impractical to try to make a water ski out of relatively short lengths of wood because of flexing in service, among other reasons, which such a ski had to undergo; whereas under my invention, such shorter pieces can be utilized in cooperative relation with longer side binder members integrally bonded thereto. Further, conventional skis on turns may readily and rapidly become unstable; whereas I optionally provide integral side supports in the form of wings which provide stability on turns enabling them to be taken at slower speed without spilling and without detrimentally increasing the forward planing drag of the skis. In addition, boats of lesser power may be utilized to tow a skier on such skis without sinking. Still further, my invention optionally may be provided in the form of a knock-down ski with removable front and back pieces which are readily rigidly attachable to the body portion of the ski made in accordance with one or more other aspects of this invention.

Other objects, features and advantages of this invention will be apparent from the following description and the accompanying drawings, which are illustrative only, in which:

FIGURE 1 is a plan view of a composite all-wood water ski embodiment of this invention;

FIGURE 2 is a side view of the ski embodiment shown in FIGURE 1;

FIGURE 3 is a view in section taken along line III—III of FIGURE 1;

FIGURE 4 is a view in section taken along line IV—IV of FIGURE 1;

FIGURE 5 is a plan view of another composite all-wood embodiment of this invention utilizing integral side supports;

FIGURE 6 is a view in side elevation of the embodiment shown in FIGURE 5;

FIGURE 7 is a view in section taken along line VII—VII of FIGURE 6;

FIGURE 8 is a view in plan of a further embodiment of a composite water ski of this invention with removable front and back pieces; and

FIGURE 9 is a view in side elevation of the further embodiment shown in FIGURE 8.

Referring to the drawings, there is shown therein a composite all-wood water ski 10, of which a pair normally are used by a water skier unless a single ski is utilized as in the case of special or slalom events when a single ski may be utilized, sometimes with a toe piece behind an adjustable foot binder 11 shown in chain line outline. Such a ski binder may be made in accordance with my application for Letters Patent Serial No. 642,101, filed February 25, 1957, now Patent No. 2,939,159, and attached to ski 10 as shown therein.

2

Composite ski 10 provides a turned up front end 12 or toe, rounded in plan at 13 and a flat back or rear end 14 which also may be rounded in plan as shown at 15. An integral body portion 16 extends between the toe 12 and heel 14 of the ski and all together provide a continuous, smooth planing surface 17 on the underside thereof and a smooth upper surface 18 in the embodiment illustrated. The central section of the ski itself extends longitudinally between unsectioned entire side binding members 19 of wood which extend the length of the ski. Such central section is made up of end-to-end and side-to-side abutting sections of wood comprising relatively short pieces which is a matter of great economy and more efficient utilization of dressed lumber used in the production of skis. Skis preferably are made of rather high quality woods including ash, maple, mahogany and others. In ski 10, the use of such a built-up wood central section also enables pleasing patterns of commercial sales appeal value to be obtained. Thus, pieces marked M may be pieces of darker mahogany and the remainder may be pieces of a lighter wood such as ash or maple. Hence, with a clear waterproof lacquer finish, ski 10 is very attractive due in part to the fact that the ski 10 can be made up of smaller pieces of contrasting wood between the side binder members 19. Or, the pieces used can be of the same color and stock if desired. Preferably, the pieces 20 are made of one thickness of solid wood, but they may be made of plywood instead, if desired.

The front and back abutting edges of the various wood sections 20 are serrated in complementary fashion as shown to provide each with a dovetailed or serration joint 21 illustrated in FIGURE 3, which joint is bonded when the matching serrations are brought together by a resorcinol base wood glue or other waterproof marine glue for wood. Such wood glues are on the market and provide a permanent bond of great strength.

The central section of ski 10 has three longitudinal courses, a central course A, a right-hand course B and a left-hand course C, at the head of each of which such letters have been placed in FIGURE 1. The front and back (cross) joints 21 of the wood pieces are displaced longitudinally in each course from any joint of the immediately adjoining course or courses. Further, side (lengthwise) joints 22 where the pieces 20 abut one another and the side binder members 19 preferably are provided with similar complementary serrations as illustrated in FIGURE 4, each joint 22 being bonded by a waterproof marine wood glue. The unsectioned and unbroken character of the side members 19 appears to lock the composite central section together in a way which prevents separation at any of the joints in the finished composite all-wood ski 10. Further, such composite skis illustrated in FIGURES 1 to 4 may be made of a relatively thinner wood for a ski of given strength and be less subject to warping, twisting or splitting.

In the modification illustrated in FIGURES 5 to 7, there are unbroken side binder members 23 of wood which extend along the entire length of the sides of composite ski 24 and serve the purpose and function of the cooperating side members 19 in the preceding embodiment. In addition, there is a longitudinal central section between members 23 comprising sections 25, 26, 27, 28 and 29, of wood, with the wood in sections 26 and 28, for example, being made of wood of a contrasting color to provide a pleasing and harmonious pattern. Cross joints 30 and longitudinally extending joints 31 between abutting such wood pieces have matching serrations on the abutment faces and such abutment faces are bonded to one another by waterproof glue in the manner previously described in connection with cross joints 21 and longitudinal joints 22.

A ski binder 32, like binder 11, is also provided on the top of each ski 24 for skiing use. The outermost longitudinal joints 31 bond a pair of shorter side wings 33 to the main portion of ski 21 and make them an integral part thereof. In cross section, as shown in FIGURE 7, the side supports 33 are curved upwardly at 34 so that the cross section is generally in the form of an arc flattened in the center. Hence, a skier using a pair of the composite skis 24 when starting out on a tow for a run will reach a planing position more quickly because he has not only the upwardly curved toe portions 35 to aid in reaching a planing position on the surface of the water but also a greater area during that period on the underside 36 of the body of the ski because of the additional area furnished by the bottom surfaces of the wings 33. And, skis 24 can be successfully towed without sinking by a slower boat than otherwise would be the case because of the somewhat greater planing surface provided in such case by the underside of each ski 24. At the same time, planing speed is not substantially reduced, or drag increased, by the wings 33 as the skis attain planing speed because of the laterally upwardly curved form of the wings 33. Further, turns may be taken with one or more skis 24 with less skill, or at slower speeds, without spilling the skier, because as the ski is tilted about its longitudinal axis, additional supporting area is brought to bear against the surface of the water due to greater surface engagement with the water by the wing on the inside of the turn.

In the further ski embodiment 37 of FIGURES 8 and 9, a flexure main body portion 38 is made of wood either in the composite form of ski 10 or of ski 24, or by longitudinal strips of wood having lengthwise joints permanently bonded together, or a single piece of wood may be used for body 38, as desired. A binder 39 is affixed thereto like and in the manner of binder 11 or 32. The front or back ends of body 38 are provided respectively with a front tenon 40 and a rear tenon 41. Front tenon 40 cooperates with a relatively close fitting socket 42 at the back of an upwardly curved front piece 43 made of wood, or of plastic which is die cast or otherwise formed. Similarly, a socket 44 in a back piece 45 closely fits around tenon 41 to complete ski 37 when it is to be used. Heel member 45 may be made of wood, or of plastic which is die cast or otherwise formed. A rudder 46 may be used as shown on the underside of member 45 and may be integral therewith if member 45 is made of plastic. Otherwise, it may be attached by means of screws or bolts. When the front and back pieces 43 and 45 are pulled off and separated from their respective tenons, ski 37 is in its "knockdown" condition and its length materially shortened, which is a great convenience for those who may wish to carry skis 37 about with them from place

5 to place. When assembled, as shown in FIGURES 8 and 9, the members 43 and 45 are rigidly held in place with the aid of the aforesaid tenons and by plates 47 and 48, respectively, which as shown are permanently fixed to body 38 by carriage bolts or rivets 49 and 50. Carriage bolts 51 and 52, after the assembly is made, are passed through predrilled holes therefor extending through the socket walls and tenons respectively to unite ski 37 in a rigid assembly, with the toe and heel pieces 43 and 45 fastened to the body 38.

10 Various details of the illustrated embodiments may be changed, and other embodiments provided, without departing from the spirit of my invention or the scope of the appended claim.

15 I claim:

A water ski, having a foot binder position thereon, comprising a longitudinally extending central section and two one-piece side binder members of single thickness on the outer sides of said central section forming lengthwise joints therewith, said central section being made up of relatively shorter pieces of wood of single thickness in front and back abutting relation forming cross joints, said cross joints being bonded together with serration joints, said lengthwise joints being bonded together, a side support member of single thickness on the outer side of each side binder member in lengthwise joint abutting relation therewith, said last-mentioned lengthwise joints being bonded together, said side support members being substantially parallel to the center line of said ski 20 and having a length comprising a minor portion of the over all length of said ski, said support members further being generally athwart said foot binder position on said water ski, said side support members further being positioned with the underside thereof extending laterally outwardly and upwardly.
